UNITED STATES PATENT OFFICE

166,662

DECORATIVE LAMP

Emil C. Fasson, Inglewood, Calif.

Application December 13, 1951, Serial No. 17,723

Term of patent 14 years

(Cl. D26—8)

To all whom it may concern:

Be it known that I, Emil C. Fasson, a citizen of the United States and resident of Inglewood, in the county of Los Angeles and State of California, have invented a new, original, and ornamental Design for a Decorative Lamp, of which the following is a specification, reference being had to the accompanying drawing, forming a part thereof.

Figure 1 is a side elevational view of a decorative lamp showing my new design; and

Figure 2 is a cross-sectional view taken along line 2—2 of Figure 1.

The dominant features of my design are shown in solid lines in the drawing.

I claim:

The ornamental design for a decorative lamp, substantially as shown and described.

EMIL C. FASSON.
